TOOTHPICK DISPENSER

Bert G. Velin, Gosta E. Velin, and Marcus H. Velin, Maple, Wis.

Application June 9, 1938, Serial No. 212,832

6 Claims. (Cl. 312—77)

The present invention relates to new and useful improvements in toothpick dispensers for use particularly in restaurants and other public places and has for its primary object to provide, in a manner as hereinafter set forth, novel means through the medium of which toothpicks will be delivered one at a time in a highly satisfactory and sanitary manner.

Other objects of the invention are to provide a toothpick dispenser of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of an embodiment of the dispenser, portions thereof being broken away.

Figure 2 is a view in vertical section through the device, showing the vertically movable toothpick container in lowered position.

Figure 3 is a view substantially similar to Fig. 2 but showing the toothpick container in elevated position.

Figure 4 is a detail view in perspective of the swinging delivery member.

Figure 5 is a view in front elevation of the toothpick container.

Figure 6 is a view in horizontal section, taken substantially on the line 6—6 of Fig. 1.

Referring now to the drawings in detail, it will be seen that the embodiment of the invention which has been illustrated comprises a cabinet 1 of suitable material which is mounted on a base 2. Access to the upper portion of the cabinet 1 is had through the medium of a suitable closure 3. A hand may be inserted in the lower portion of the cabinet 1 through an opening 4 in the lower front portion of said cabinet. The reference number 5 designates pairs of guide rails which are mounted vertically on the side walls 6 of the cabinet 1.

Mounted for vertical sliding movement in the cabinet 1 is a container 7 for the reception of toothpicks, said container being open at its top. Vertical flanges 8 project from the sides of the container 7 and are slidably engaged between the guides 5. The front 9 of the container 7 has formed therein, at an intermediate point, a

transversely elongated opening 10. This is shown to advantage in Fig. 3 of the drawings. The toothpick container 7 is operable between a vertical partition 11 in the cabinet 1 and the back 12 of said cabinet. The partition 11 extends upwardly from the opening 4 between the side walls 6 of the cabinet 1 and in spaced, opposed relation to the front 13 of said cabinet. The partition 11 terminates, at its upper end, at an intermediate point in the cabinet 1. Mounted 10 on one of the side walls 6 of the cabinet 1 in spaced relation above the partition 11 is an inclined deflector 14 the purpose of which will be presently set forth.

Hingedly mounted in the lower portion of the opening 10 of the container 7 is a swinging delivery member 15. The member 15 has formed transversely in its lower portion a pocket 16 of a size to receive but a single toothpick. Hinge eyes 17 on the lower edge of the member 15 receive a suitable pivot rod 17 which is mounted transversely on the front wall 9 of the container 7 closely adjacent the lower portion of the opening 10. It may be well to here state that the member 15 also functions as a hinged closure for the opening 10 in the container 7. Projecting from one end of the member 15 is an arm 18 which is engageable beneath the deflector 14 for positively causing said member 15 to swing outwardly and downwardly after it clears the partition 11 when the container 7 is elevated in the cabinet 1.

The container 7 has mounted therein a false bottom 19 on which the toothpicks rest, said false bottom comprising a plurality of sections 20 35 hingedly connected, as at 21. One end of the false bottom 19 is hinged on the rod 17 in the lower portion of the opening 10 of the container 7. The other end of the false bottom 19 is suspended on a flexible strand 22 which is trained 40 over a pulley 23 on the upper portion of the back 12 of the cabinet 1 and connected to the back of the container 7.

It is thought that the operation of the device will be readily apparent from a consideration of the foregoing. The closure 3 permits the container 7 to be filled from the top of the cabinet 1, the supply of toothpicks resting on the false bottom 19. With the container 7 in lowered position, as seen in Fig. 2 of the drawings, the member 15 is held closed over the opening 10 by the partition 11. Also, when the container 7 is in lowered position, the false sectional bottom 19 is elevated and inclined toward the opening 10 for causing a single toothpick to enter the pocket 16 55

of the member 15 by gravity and rest therein. Now, when a toothpick is desired, a hand is inserted, palm up, in the lower portion of the cabinet 1 through the opening 4 and the fingers of 5 that hand are engaged beneath the container 7. The container 7 is then elevated to substantially the position shown to advantage in Fig. 3 of the drawings. When the member 15 clears the upper end of the partition 11 it swings outwardly 10 and downwardly to open position and the toothpick in the pocket 16 thereof drops by gravity through the passage 24 defined in the cabinet 1 by said partition 11 and the front 13 of said cabinet into the upturned hand. The deflector 15, located in the path of the arm 18, provides positive means for causing the member 15 to swing outwardly and downwardly when the container 7 is raised. As the container 7 is raised the hinged sectional false bottom 19 is lowered by 20 the flexible strand 22 in a manner to prevent the supply of toothpicks resting on said false bottom from escaping through the opening 10. When the container 7 is released it returns by gravity to lowered position. When this occurs the member 25 15 is swung upwardly to closed position and maintained in closed position by the partition 11. Of course, when the container 7 returns to lowered position the false bottom 19 again assumes the position shown in Fig. 2 of the drawings and 30 another toothpick drops into the pocket 16 of the member 15.

It is believed that the many advantages of a tooth-pick dispenser constructed in accordance with the present invention will be readily understood and although a preferred embodiment of the 35 device is as illustrated and described, it is to be understood that changes in the details of construction and in the combination and arrangement of parts may be resorted to which will fall within the scope of the invention as claimed.

40 What is claimed is:

1. A toothpick dispenser comprising a cabinet, a container, for the reception of toothpicks, mounted for vertical sliding movement in said cabinet, said container having a discharge opening therein, a delivery member mounted for swinging movement on the container and having a pocket therein for receiving a toothpick from the container through the discharge opening, and means in the cabinet for actuating the delivery member when the container is raised and lowered.

2. A toothpick dispenser comprising a cabinet, a container, for the reception of toothpicks, mounted for vertical sliding movement in said cabinet, said container having a discharge opening therein, a delivery member mounted for swinging movement on the container and having a pocket therein for receiving a toothpick from the container through the discharge opening, means in the cabinet for actuating the delivery member when the container is raised and lowered, and a vertical partition in the cabinet in spaced, opposed relation to one of the walls thereof, said partition terminating, at its upper end, at an intermediate point in the cabinet and defining, in conjunction with said one wall of said cabinet, a discharge passage for the toothpicks.

3. A toothpick dispenser comprising a cabinet, a container, for the reception of toothpicks, mounted for vertical sliding movement in the cabinet, said container having a discharge opening therein, a delivery member hingedly mounted on the container for receiving toothpicks through the discharge opening, means in the cabinet for 70 controlling and actuating the delivery member

when the container is raised and lowered, and means in the container for supporting and elevating the toothpicks for discharge by gravity into the delivery member when the container is in lowered position and for lowering the toothpicks 5 below the discharge opening when the container is in elevated position.

4. A toothpick dispenser comprising a cabinet, a container, for the reception of toothpicks, mounted for vertical sliding movement in the cabinet, said container having a discharge opening therein, a delivery member hingedly mounted on the container for receiving toothpicks through the discharge opening, means in the cabinet for controlling and actuating the delivery member when 10 the container is raised and lowered, and means in the container for supporting and elevating the toothpicks for discharge by gravity into the delivery member when the container is in lowered position and for lowering the toothpicks below 20 the discharge opening when the container is in elevated position, the last named means including a false bottom in the container having one end hingedly connected thereto adjacent the lower portion of the discharge opening, and a flexible 25 element supported on the cabinet and having one end connected to the other end of the false bottom and its other end connected to said container.

5. A toothpick dispenser comprising a cabinet having a hand receiving opening in the lower portion thereof, a container, for the reception of toothpicks, mounted for vertical sliding movement in said cabinet, said container having a discharge opening therein at an intermediate point, a vertical partition in the cabinet in spaced, opposed 30 relation to the front wall thereof, said partition terminating, at its upper end, at an intermediate point in the cabinet, said partition in conjunction with the front wall of the cabinet, defining a vertical discharge passage communicating, at its 35 lower end, with the first named opening, a closure member for the second named opening hingedly mounted on the container for swinging movement in a vertical plane, said member having a pocket therein for the reception of a single 40 toothpick through the discharge opening of the container, the partition being engageable with said member for actuating same to closed position and for maintaining said member in closed position when the container is in lowered position in the 45 cabinet, said member being operable over the upper end of the partition when the container is elevated for discharging the toothpick in the pocket into the delivery passage, coacting means on the member and cabinet for positively opening said member when the container is raised to elevated position, and means in the container for elevating the toothpicks when said container is in lowered position and for lowering said toothpicks when said container is in elevated position. 50

6. A toothpick dispenser comprising a cabinet having a hand receiving opening in the lower portion thereof, a container, for the reception of toothpicks, mounted for vertical sliding movement in said cabinet, said container having a discharge opening therein at an intermediate point, a vertical partition in the cabinet in spaced, opposed relation to the front wall thereof, said partition terminating, at its upper end, at an intermediate point in the cabinet, said partition, in 65 conjunction with the front wall of the cabinet, defining a vertical discharge passage communicating, at its lower end, with the first named opening, a closure member for the second named opening hingedly mounted on the container for swinging 70

movement in a vertical plane, said member having a pocket therein for the reception of a single toothpick through the discharge opening of the container, the partition being engageable with 5 said member for actuating same to closed position and for maintaining said member in closed position when the container is in lowered position in the cabinet, said member being operable over the upper end of the partition when the 10 container is elevated for discharging the toothpick in the pocket into the delivery passage, co-acting means on the member and cabinet for positively opening said member when the container is raised to elevated position, and means 15 in the container for elevating the toothpicks when said container is in lowered position and for low-

ering said toothpicks when said container is in elevated position, said means including a false bottom mounted in the container for swinging movement in a vertical plane, said false bottom comprising a plurality of hingedly connected sections, one end of said false bottom being hingedly connected to the container adjacent the lower portion of the discharge opening, a pulley mounted in the cabinet, and a flexible element trained over said pulley and having one end connected 10 to the other end of the false bottom and its other end connected to the container. 5
